US0D1113852S

(12) **United States Design Patent** (10) Patent No.: **US D1,113,852 S**
(45) Date of Patent: ** Feb. 17, 2026

(54) **WIRELESS EARPHONE**

(71) Applicant: **Samsung Electronics Co., Ltd.**, Suwon-si (KR)

(72) Inventors: **Sangok Sohn**, Suwon-si (KR); **Sanhui Oh**, Suwon-si (KR); **Kyubok Lee**, Suwon-si (KR); **Joohyung Kim**, Suwon-si (KR); **Dongjae Koo**, Suwon-si (KR)

(73) Assignee: **Samsung Electronics Co., Ltd.**, Suwon-si (KR)

(**) Term: **15 Years**

(21) Appl. No.: **29/928,141**

(22) Filed: **Feb. 8, 2024**

(30) **Foreign Application Priority Data**

Aug. 11, 2023 (KR) 30-2023-0031409

(51) LOC (15) Cl. 14-01

(52) U.S. Cl.

(57) **CLAIM**

The ornamental design for a wireless earphone, as shown and described.

DESCRIPTION

FIG. 1 is a front perspective view of a wireless earphone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of a wireless earphone that form no part of the claimed design.

1 Claim, 4 Drawing Sheets
